UNITED STATES PATENT OFFICE.

DAVID M. HOLBROOK, OF PORTLAND, OREGON.

INCUBATOR.

Application filed August 20, 1925. Serial No. 51,427.

The invention relates to improvements in incubators, and its object is to provide new and improved electrical heating means embodying heating coils and unique supporting means therefor, the latter being of a nature to prevent direct downward radiation of heat onto the eggs.

With the foregoing in view, the invention resides in the novel subject matter hereinafter described and claimed, the description being supplemented by the accompanying drawings.

Figure 1 is a longitudinal sectional view through an incubator constructed in accordance with my invention.

Figure 2 is a horizontal sectional view on line 2—2 of Fig. 1, looking in the direction of the arrows, and this view indicates by the line 1—1, the planes on which Fig. 1 is cut.

Figure 3 is an enlarged detail longitudinal sectional view as indicated by line 3—3 of Fig. 2.

Figure 4 is a vertical transverse section on line 4—4 of Fig. 1.

Figure 5 is a diagram showing the heating coils and wiring, together with a thermostatic switch therefor.

In the drawings above briefly described, the numeral 1 designates an incubation chamber which may be of any known or preferred construction, the chamber herein disclosed, being provided with a plurality of egg trays 2.

Projecting downwardly from the top of the chamber 1, I have shown a plurality of binding posts 3 which are preferably provided with prongs 4 driven into said top. These binding posts may be at any desired locations, according to the positions to be occupied by the heating coils 5, which coils have their ends detachably mounted by said posts. Suitable conducting wires 6 may connect adjacent ends of the coils as may be necessary, and the main feed wires 8 are in electrical connection with two of the posts 3, the upper ends of the latter having auxiliary posts 9 to which the wires are clamped. Included in the circuit at any desired point, is a thermostatic switch 10 of any adequate construction.

Horizontally disposed insulating bars 11 extend longitudinally under the coils 5 and are provided with channels 12 in which said coils are received, said bars being supported

by screws 13, by staples 14, or in practically any other desired manner. The supporting means for the bars are preferably driven into the top of the chamber 1 in a manner permitting their removal whenever it is necessary to gain access to any of the coils 5, for instance, for replacing or repairing. These bars not only prevent the intermediate portions of the coils from sagging, but they prevent direct downward radiation of heat onto the eggs from said coils, producing a more efficient distribution of the heat in the chamber. At this point, it may be stated that by preference, the coils 5 near the walls of the chamber 1, contain more wire than those at the central portions, thus providing for more heat around the walls, where needed.

Extending through the back wall of the chamber 1, above the egg trays 2, I have shown a number of fresh air inlet tubes 15, said tubes being equal in number to the trays 2 and having their inner ends disposed substantially over the centers of these trays. Passing through the top of the chamber 1, are a number of air outlets 16 which are also preferably disposed one over each tray 2, the combined air conducting capacities of the outlets 16 being about the same as the combined capacities of the tubes 15. Slides 17 or the like are provided for closing the outlets 16 for a purpose to appear.

The bottom of the chamber 1 is formed with groups of auxiliary air inlet perforations 18, one group being disposed under each of the trays 2. The combined conducting capacities of all of the perforations 18 are considerably less than the combined conducting capacities of the main air inlet tubes 15. Hence, as long as the slides 17 are open, very little air will enter through the perforations 18, but an abundance of fresh air will enter through the tubes 15 and this air will escape through the outlets 16, as it becomes heated. This rapid circulation of air is used almost entirely while the eggs are in the incubator. During the first few days of the hatch however, the top slides should be closed. Then, fresh air in relatively small quantities enters through the perforations 18, slowly circulates in the chamber 1, and escapes through the tubes 15, providing the desirable ventilation during the hatching period. It may be further explained that the perforations 18 serve to supply fresh air

to the nursery 19, insuring that the chicks shall obtain a healthy start in life.

For supplying the necessary humidity to the chamber 1, I have provided a water tank 5 20 which is preferably elongated horizontally, said tank having longitudinal slots 21 in its sides, through which moisture can escape into said chamber. This tank is equipped with an upstanding neck 22 which 10 passes through and is secured to the top 1, the upper end of said neck being equipped with a slide or the like 23. When this slide is closed, moisture escapes from the water tank through the slots 21 into the chamber 1. 15 When the slide is open however, moisture escapes through the neck 22 and is not supplied in noticeable quantity to the chamber. By properly regulating the slide or the like, the desired humidity within the chamber 20 may be readily obtained.

The ventilating and humidifying means herein disclosed, constitute no parts of the invention claimed in this application.

I claim:—

25 In a heating means for an incubation chamber, one pair of heating coils disposed in axial alinement with each other under the top of the chamber, a second pair of axially alined coils similarly disposed and positioned 30 in parallel relation with the coils of the first named pair, binding posts secured to the chamber top and detachably anchoring the inner and outer ends of the coils of the first

and second mentioned pairs, third and fourth pairs of coils extending transversely between the outermost of the aforesaid binding posts and having their outer ends detachably held thereby, additional binding posts secured to the chamber top and detachably holding the inner ends of the coils of said third and 40 fourth pairs, a fifth pair of axially alined coils disposed between and parallel with the first and second named pairs, binding posts to which the ends of the coils of said fifth pair are detachably connected, an eleventh 45 coil between the first and second named pairs of coils and parallel therewith, binding posts to which the ends of said eleventh coil are detachably connected, transverse connectors between these binding posts and those at the 50 outer ends of said fifth pair of coils, transverse connectors between the binding posts at the inner ends of said fifth pair of coils and the binding posts at the inner ends of the first named pair of coils, and current feed 55 wires connected to the binding posts at the inner ends of the second pair of coils, the coils of said fifth pair containing less wire than the coils of the first or second named pairs, said eleventh coil also containing less 60 wire than either the first or second named pairs of coils.

In testimony whereof I have hereunto affixed my signature.

DAVID M. HOLBROOK.
